ton, Mass.

Application April 16, 1937, Serial No. 137,249

4 Claims. (Cl. 62—117)

This invention relates to air conditioning systems for passenger vehicles and relates more particularly to spray type air conditioning systems utilizing refrigeration, for railway passenger cars.

According to this invention a spray type air conditioning system utilizing mechanical refrigeration is provided for a railway passenger car. Water is chilled by evaporator coils which are preferably mounted on the under side of the car and this water is pumped to an air washer preferably mounted above the passenger space.

According to a feature of this invention, the water returned from the air washer is frequently changed by the removal of a portion which is passed in heat exchange relationship to the condenser of the refrigeration equipment, and by the replacement of the removed portion from a water make-up tank. Thus the spray water is maintained fresh; impurities are removed, and the refrigeration costs are reduced by the use of the chilled exhausted water for assisting in the condensing action.

According to another feature of this invention, when the wet bulb temperature of the outside air is below a predetermined point, the refrigeration apparatus is shut down, the recirculated air normally supplied to the air washer is discontinued, and the air washer cools the outside air by evaporative cooling.

According to another feature of this invention, the air washer includes coil pre-coolers through which chilled water is circulated and over which chilled water is sprayed, the coils thus acting to clean as well as cool the air.

An object of this invention is to efficiently cool and clean the air supplied to a passenger vehicle.

Another object of the invention is to provide a spray type conditioning system for a passenger vehicle, normally supplied with chilled water from mechanical refrigeration equipment, and which is converted for evaporative cooling when the wet bulb temperature of the outside air is sufficiently low.

Another object of the invention is to provide for a passenger vehicle, a combined spray type and coil type air conditioner supplied with chilled water from mechanical refrigeration equipment.

Other objects of the invention will be apparent from the following description taken together with the drawing.

The invention will now be described with reference to the drawing which illustrates diagrammatically one embodiment of an air conditioning system according to this invention.

The air conditioner 5 is located in one end and

on the roof zone of a railway passenger car. It contains the spray nozzles 6 which spray water into and in a direction opposed to the movement of, the air entering the conditioner from the blower 1. The conditioner 5 also contains the 5 four rows of precooler tubes 8 and above the tubes 8 are arranged the spray nozzles 9 which spray water downwardly upon the tubes 8. By providing the tubes 8 in the conditioner, such additional surface is provided that the conditioner 10 5 may be smaller than were the sprays alone used, and by spraying water on the tubes 8 they are kept clean and also act to clean the entering air.

Water from the sump 10 is supplied by the 15 pump 11, driven by the motor 12, through the pipes 13 and 14. A portion of the water supplied through pipe 13 is supplied through pipe 15 to the tubes and from these tubes is returned to the sump 10 through pipe 16.

The water sprayed in the conditioner 5 is collected in the trough 17 and returned through the pipes 18 to the sump 10.

The tank 19 supplies make-up water to the sump 10. The water in the sump 10 is chilled 25 through being circulated by the pumps 20 driven by the motor 21, through the evaporator 42 which it enters through the pipe 22 and leaves through pipe 23.

The compressor 24, driven by motor 25, compresses any suitable refrigerant which then passes through the condenser 26, the expansion valve 27 and evaporator coils 28.

Water from the sump 10 is drained out through the pipe 29 and is sprayed through the nozzles 30 35 upon the coils of the condenser 26. The amount of this water is regulated by the valve 31. The valve 32 between the make-up tank 19 and the sump 10, is adjusted to admit to the sump 10 from the make-up tank 19 an amount of water 40 equal to that drained from the sump and sprayed upon the condenser coils.

The water thus drained from the sump 10 gradually changes the water sprayed in the conditioner 5 and not only maintains the spray water 45 fresh but removes the impurities collected from the air by the water sprayed in the conditioner 5. The water thus drained from the sump 10 is chilled water and its "cold energy" is not wasted but effectively made use of for condensing the 50 refrigerant.

In some locations the wet bulb temperature of the outside air is at times below, say 60° F. and when this occurs, evaporative cooling may be effectively used. Accordingly, this invention uti- 55

lizes evaporative cooling when feasible, for effecting savings in refrigeration and corresponding savings in operating cost.

The wet bulb thermostat 33 mounted in the outside air intake closes, when the wet bulb temperature of the outside air is above 60° F., circuits energizing from the electric source 34, the compressor 25, the pump motor 21 and the damper motor 35. This causes the damper motor 35 to operate to open the damper 36 in the recirculated air inlet 37; the motor 25 to operate the compressor 24, and the motor 21 to operate the pump 20 to supply chilled water from the evaporator 42 to the sump 10. At this time the system operates in a refrigerative cooling cycle with ice water supplied to the conditioner 5 which conditions both outside and recirculated air.

When the wet bulb temperature falls below 60° F., the thermostat automatically opens the energizing circuits of the damper motor 35, the pump motor 21 and the compressor motor 25. When this happens the recirculated air dampers 36 are closed and the pump 11 supplies water from the sump 10 to the conditioner 5, which water is recirculated between the sump 10 and the conditioner 5 to effect evaporative cooling of the outside air.

The dry bulb thermostat 38 mounted in the passenger space controls the temperature there by starting and stopping the pump motor 12 to control the supply of water from the sump 10 to the conditioner 5.

The steam heater 39 supplied with steam from the source 40 is mounted in the output side of the conditioner 5 to provide heating of the air when this is desired.

The conditioner air from the conditioner 5 may be supplied into the passenger space of the car through any well known type of distributing duct or bulk head discharge arrangement or in any other suitable manner.

While one embodiment of the invention has been described for the purpose of illustration, it should be understood that the invention is not

limited to the exact apparatus and arrangement described as many departures may be made by those skilled in the art without departing from the spirit of the invention.

What is claimed is:

1. An air conditioning system for a passenger vehicle comprising an air cooler, an evaporator for cooling water, refrigerating means including a condenser for supplying a refrigerant to said evaporator, means for supplying water chilled by said evaporator to said cooler, and means for spraying a portion of the water returned from said cooler upon said condenser and for then discharging it from said vehicle.

2. An air conditioning system for a passenger vehicle comprising an air cooler, an evaporator for cooling water, refrigerating means including a condenser for supplying a refrigerant to said evaporator, means for supplying water chilled by said evaporator to said cooler, means for spraying a portion of the water returned from said cooler upon said condenser and for then discharging it from said vehicle, a water make-up tank, and means for supplying water from said tank to said evaporator.

3. An air conditioning system for a passenger vehicle comprising an air cooler, a sump, an evaporator, means for circulating water through said sump and said evaporator, means for circulating water through said sump and said cooler, a condenser associated with said evaporator, and means for spraying water from said sump upon said condenser and for then discharging it from said vehicle.

4. An air conditioning system for a passenger vehicle comprising an air cooler, a sump, an evaporator, means for circulating water through said sump and said evaporator, means for circulating water through said sump and said cooler, a condenser associated with said evaporator, means for spraying water from said sump upon said condenser and for then discharging it from said vehicle, a water make-up tank, and means for adding water from said tank to said sump.
